DESIGN FOR A MEDAL

John F. X. Landrigan, Bayonne, and George W. Crone, Jersey City, N. J., assignors to New Jersey State Council of the Knights of Columbus, Bayonne, N. J.

Application April 16, 1941, Serial No. 100,412

Term of patent 14 years

To all whom it may concern:

Be it known that we, John F. X. Landrigan and George W. Crone, citizens of the United States, residing, respectively, at Bayonne, in the county of Hudson, State of New Jersey, and Jersey City, in the county of Hudson, State of New Jersey, have invented a new, original, and ornamental Design for Medals, of which the following is a specification, reference being had to the accompanying drawing, forming part thereof.

Figure 1 is a plan view of a medal, showing our new design, and Figure 2 is a section along the line 2—2 of Figure 1.

We claim:

The ornamental design for a medal, as shown.

JOHN F. X. LANDRIGAN.
GEORGE W. CRONE.
